UNITED STATES PATENT OFFICE.

WILLIAM M. SMITHER, OF KEENE, KENTUCKY.

TRACE-CARRIER.

SPECIFICATION forming part of Letters Patent No. 297,864, dated April 29, 1884.

Application filed January 31, 1884. (No model.)

To all whom it may concern:

Be it known that I, WILLIAM M. SMITHER, a citizen of the United States, residing at Keene, in the county of Jessamine and State of Kentucky, have invented certain new and useful Improvements in Trace-Carriers, of which the following is a specification, reference being had therein to the accompanying drawings.

10 My invention relates to carriers for trace-chains in harness; and the improvement which I have made relates to a swinging hook which carries the chain in such manner that, while the hook is connected to the back-band, it will 15 not cause said band to be moved out of position when in use.

In the accompanying drawings, which make part of this specification, Figure 1 represents a side view, and Fig. 2 a longitudinal section, 20 of my invention.

In the figures, A represents the back-band of a set of harness.

B represents a loop, which is connected to this band by headed rivets *a a'*. This loop 25 may be made of metal, but I preferably make it of leather.

C represents a metallic hook, (for the purpose of carrying the chain,) which is secured within this loop.

30 *e* represents a metallic plate provided with two lugs cast on its surface, and through which the rivets pass, and *i* a metal or leather filling placed between the two ends of the loop B, and between which the upper end of the hook C is

secured by the lower lug through which passes 35 one of the rivets *a'*, and which acts as a pivot upon which it vibrates. The chain D passes through the loop B, and when suitably adjusted as to length, one of its links is caught upon the hook C, said hook having a slight 40 and suitable obstruction formed upon its point, to act as a keeper to some extent, to prevent the link from leaving the hook.

In the operation of this hook, it will readily be seen that owing to its pivotal connection to 45 the back-band, it will swing or vibrate in the line of longitudinal movement of the chain, and while carrying said chain will not disarrange the position of the back-band.

Having thus fully described my invention, 50 what I claim as new, and desire to secure by Letters Patent, is—

In a trace-carrier, the combination, with the loop, of a pendulous hook pivoted in the upper end of the said loop, and adapted to vibrate 55 or swing in the direction of the chain or trace, and a plate having on its surface a lug which forms the pivot on which the hook swings, the parts being secured together and to the back-band of a harness by rivets, one of which passes 60 through the lug on the plate, as and for the purpose described.

In testimony whereof I affix my signature in presence of two witnesses.

WILLIAM M. SMITHER.
